UNITED STATES PATENT OFFICE.

LEWIS A. MARCUS, OF NEW YORK, N. Y.

SIFTER.

Application filed May 21, 1928. Serial No. 279,538.

This invention relates to sifters or screens and more particularly to that type of sifter adapted for household use for sifting ashes.

The invention will accordingly be herein 5 after described with relation to such use and purpose, altho it is, of course, to be understood that with slight modification in size and dimensions, it is equally applicable to other purposes.

10 One of the objects of the present invention is to provide a simple and practical ash sifter, which may be inexpensively manufactured and assembled.

15 A further object is to provide a device of the above general character of strong and durable construction adapted to fit various sizes of ash receptacles or cans.

20 A further object is to provide a device of the above character of compact construction, and which will occupy a minimum amount of space when packed and shipped, thereby reducing the sales cost.

25 A further object is to provide an ash sifter of the above character, which may be easily operated and which will give a combined rotary, oscillating and reciprocatory movement, thereby more efficiently and effectively screen the ashes.

30 Other objects will be in part obvious from the annexed drawing and in part hereinafter indicated in connection therewith by the following analysis of this invention.

35 This invention accordingly consists in the features of construction, combination of parts and in the unique relation of the members and in the relative proportioning and disposition thereof, all as more completely outlined herein.

40 To enable others skilled in the art to fully comprehend the underlying features thereof that they may embody the same by the numerous modifications in structure and relation contemplated by this invention, drawings depicting a preferred form of the invention 45 have been annexed as part of this disclosure, and in such drawings, like characters of reference denote corresponding parts throughout all of the views, of which—

50 Fig. 1 is a sectional elevational view of the complete device;

Fig. 2 is a plan view with the cover removed; and

Fig. 3 shows a modified form of handle connection.

55 Referring to the drawings in detail, and more particularly to Fig. 1, 5 indicates the

upper part of an ash or trash barrel or can of any ordinary size and upon which the ash sifter is adapted to rest. It will be noted that the sifter comprises a substantially cylindrical casing 6 having a flared and stepped base 7 terminating in a reinforcing bottom bead 8. Such construction not only provides strength and durability to the device, but the stepped shoulders 7^a and 7^b permit it to be 60 placed on cans of different sizes. The inner annular shoulder 7^a is of a diameter to snugly fit a No. 7 ash can, for instance, whereas the outer shoulder 7^b fits a can of larger diameter such as a No. 8 ash can. This casing 6 terminates at its upper end in a reinforcing bead 10 upon which rests a plurality of outwardly and downwardly extending carrier straps or lugs 11 riveted or otherwise permanently secured at 12 to the inside upper part of the 65 sifting screen.

In the present case, there are four of these supporting lugs 11, but obviously a greater number may be provided for if circumstances demand.

70 The sifter or screen in the present case is preferably formed of a strip of sheet metal 13, the ends of which are suitably secured together by soldering, welding, or the like, thereby providing a cylindrical drum fitting 75 within the casing 6. The bottom 15 of the screen is perforated throughout, as indicated in Fig. 2, and provided with a reinforcing flange 16 adapted to be permanently secured to the vertical walls 13 of the sifter thereby 80 providing a strong and durable construction.

85 By referring to Fig. 1, it will be noted that one of the straps or lugs 11 extends the depth of the drum 13, and is secured thereto as by the rivets 14. The outer end of this 90 strap is preferably slightly longer than the other straps and a detachable handle 17 is secured thereto as by means of a threaded wing nut 18. The purpose of this construction is to provide a firm connection for the 95 handle and for convenience in manufacture and assembly, and it also reduces the cost of packing. Devices of this character are generally made ready for shipment and sale by placing the same in card-board boxes of minimum dimensions, and if this handle were not detachable, the size of the box would necessarily be materially increased, thereby correspondingly increasing the cost of sale.

100 As shown in Fig. 3, however, the handle 17 may be permanently secured to the downwardly extending portion 20 of the support-

ing arm 11 by means of a rivet 21. The device is, of course, provided with a suitable cover 22 thereby to prevent a spreading or flying of the small ash particles when the device is being operated. The cover is of a diameter sufficient to enclose within its downwardly extending outer flange 24 the straps 11 and is supported loosely thereon, yet so effectively that little or no dust escapes from the sifter.

10 A handle 23 permits the removal of this cover.

The operation of the device will doubtless be obvious from the above and to those familiar with the subject. It is sufficient to state, however, that the casing 6 is placed over the 15 ash barrel 5, the cover 22 removed and the ashes to be screened placed within the sifter 13. The cover is then placed over the top of the screen and the handle oscillated back and forth, and by reason of the length of the portions 11 of the supporting lugs, the sifter may likewise be given a slight reciprocatory movement, thereby to change the position of the coal or ashes relative to the openings in the bottom 15. In this manner, a compound 20 movement is given the ashes, thus greatly increasing the efficiency of the device. After a relatively short period of time, the ashes will have been thoroughly screened and the cover is removed and the coal dumped back into a 25 storage receptacle for further use.

30 From the above, it will be clear that the present invention provides a simple and practical ash sifter particularly adapted for house-hold use, which may be inexpensively manufactured, assembled and sold. The device is of strong and durable construction well adapted to withstand the severe use to which it is put. In short, the invention is believed to accomplish, among others, all of the objects 35 and advantages herein set forth.

40 Without further analysis the foregoing will so fully reveal the gist of this invention that others can by applying current knowledge readily adapt it for various applications 45 without omitting certain features that, from the standpoint of the prior art, fairly constitute essential characteristics of the generic or specific aspects of this invention, and therefore such adaptations should and are intended to be comprehended within the meaning

and range of equivalency of the following claims.

I claim—

1. In an ash sifter of the character described, in combination, a casing member having a flared bottom provided with stepped annular shoulders of different diameters to fit different size ash receptacles, a sifter screen having outwardly and downwardly extending straps adapted to hook over the top of said casing, a handle secured to one of said straps, whereby the sifter may be given a rotary and reciprocatory movement, and a cover for said sifter.

2. In an ash sifter of the character described, in combination, a cylindrical sheet metal casing having a flared bottom adapted to rest on the top of an ash barrel, a cylindrical screen having a perforated bottom fitting loosely within said casing, a plurality of 70 straps extending outwardly and downwardly from the top of said screen and resting freely upon the top of the casing, whereby the screen may be given a rotary movement, one of the straps being secured to the inside of the 75 screen throughout its depth, a handle detachably secured to said strap for moving said screen, and a cover loosely fitting the top of said screen and extending over the straps and resting thereon.

80 3. In an ash sifter of the character described, in combination, a cylindrical sheet metal casing having beaded top and bottom edges, the lower part of said casing being flared and provided with stepped annular shoulders of different diameters to fit different size ash receptacles, a cylindrical screen member loosely fitting within said casing and provided with a plurality of outwardly and downwardly extending straps resting loosely 90 on the upper beaded edge of said casing, one of the straps being secured to the inside of the screen member throughout its depth, a detachable handle secured to the other end of said strap whereby the screen may be given a rotary movement, and a cover provided with a removable handle resting upon said lugs.

95 Signed at New York, New York, this 19th day of May, 1928.

LEWIS A. MARCUS.
